BOOKMARK

Emil Polak, Woodside, Long Island, N. Y.

Application December 11, 1945, Serial No. 634,177

2 Claims. (Cl. 116—119)

1

This invention relates to new and useful improvements in a book mark.

The invention has for an object the construction of a book mark which is characterized by an inverted U-shaped resilient strip adapted to be engaged on the top portion of the back of the binding of a book and at its top end having a forwardly projecting section, a top strip associated with said U-shaped strip and section in a certain manner, and a mark proper associated with the top strip.

More specifically, it is contemplated to hingeably mount the top strip on the rear of the U-shaped strip and to provide it with a jaw portion engageable over said forwardly projecting section for locking the U-shaped strip closed upon the binding of the book.

Still further it is contemplated to provide the top strip with a horizontal forwardly extending end portion, and to provide a U-shaped strip pivotally mounted at its ends upon said forwardly extending portion and to pivotally depend the mark proper from the outer end of the U-shaped strip.

Still further the invention contemplates the provision of an auxiliary strip on the top strip engageable with one arm of the U-shaped strip for frictionally holding the latter in various positions.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a fragmentary perspective view of a book with a book mark mounted thereon and constructed in accordance with this invention.

Fig. 2 is a fragmentary vertical sectional view of Fig. 1 showing the book mark in elevation.

Fig. 3 is a perspective view of the book shown in Fig. 1 opened up and with the book mark proper pulled out and swung backwards.

Fig. 4 is a fragmentary enlarged elevational view of a portion of the book mark looking in the direction of the line 4—4 of Fig. 2.

Fig. 5 is an elevational view of a book mark constructed in accordance with a modification of this invention.

The book mark in accordance with this invention, includes an inverted U-shaped strip 10 of resilient material having a front arm 10^a and a rear arm 10^b. This U-shaped strip is adapted

2

to engage upon the top portion of the back of the binding 11^a of a book 11. The front arm 10^a is somewhat shorter than the rear arm 10^b. These arms have their bottom ends formed with coiled portions 12^a respectively, directed inwards and calculated to more firmly grip and engage the binding of the book. The front arm 10^a is provided with a forwardly projecting section 10^{aa} at its top which is adapted when pressed rearwards to lock the arms 10^a and 10^b together upon the binding of the book.

A top strip 14 is provided with a coiled rear end 14^a engaging pivotally upon a pintle 15 mounted upon a pair of lugs 16 arranged upon the sides of the arm 10^b of the U-shaped strip 18. These lugs 16 are formed integral with the material of the U-shaped strip. The top strip 14 has a jaw portion 14^b normally snapped over the forwardly projecting section 10^{aa} of the U-shaped strip 10 for locking the U-shaped strip closed and assisting in maintaining itself on the binding of the book. The top strip 14 is also provided with a forwardly extending end portion 14^c extending forwards from the jaw portion 14^b.

25 A substantially U-shaped strip 18 is pivotally mounted at the ends of its arms upon the forwardly extending end portion 14^c by a pintle 19. The arms of the U-shaped strip 18 engage respectively above and below the end portion of 20 the forwardly extending end portion 14^c. The pintle 19 engages through these three parts.

A marker proper 20 pivotally depends from the outer end of the U-shaped portion of the U-shaped strip 18. This mark proper comprises a 35 flat piece of material 20^a mounted upon the bottom end of a relatively thin stem 20^b. This stem extends into a slot 21 formed in the bend of the U-shaped strip 18. The inner end of the stem 20^b is provided with a spherical head 20^c which 40 forms a bearing by which the mark proper 20 may be pivoted upwards and downwards. The mark proper 20 may move from the vertical position illustrated in Fig. 2 upwards substantially to a horizontal position above the pages 11^b of the book 11.

The operation of the device is as follows:

In Figs. 1 and 2 the book mark is shown in actual use. The mark proper 20 may be engaged between different pages merely by pivoting it upwards above the top edges of the pages 11^b and then swivelling the U-shaped strip 18 to the right or left, as desired, and allowing the mark proper 20 to then move downwards into its new position. The book mark may be removed from the book by 55 first pivoting the top strip 14 upwards so that its

jaw portion 14^b disengages from the forwardly projecting section 10^{aa} of the U-shaped strip 10. Fig. 3 illustrates the parts in this position. Now the U-shaped strip 10 may be pulled off the binding 11^a of the book.

In Fig. 5 a modified form of the invention has been disclosed which distinguishes from the prior form in the fact that the top strip 14' has a bottom continuation 14^d continuing from the pivot 15 frontwise and extending over the top of the U-shaped strip 10 and continuing into a jaw portion 14^{bb} disposed directly beneath and engaged by the jaw portion 14^b. The jaw portion 14^{bb} engages over and holds the forwardly projecting portion 10^{aa}. The jaw portion 14^b supplements the holding action of the jaw portion 14^{bb}.

A forwardly extending end portion 14^e continues from the jaw portion 14^{bb} and extends to a position directly beneath the bottom arm of the U-shaped strip 18. A piece of friction material 22 is cemented upon the top face of the end portion 14^e and frictionally engages the bottom face of the bottom arm of the U-shaped strip 18 for frictionally holding the U-shaped strip 18 in various pivoted positions upon the pintle rivet 19. In other respects this form of the invention is similar to the previous form.

A feature of this form of the invention resides in the fact that the U-shaped strip 18 is not loose, in that it is frictionally held by the forwardly extending portion 14^e. However, the U-shaped strip 18 may easily be moved to one side or the other when required. Moreover, the U-shaped strip 10 will be maintained better upon the binding of the book since it is held in position by a double jaw construction, namely, the jaw portions 14^{bb} and 14^b.

While I have illustrated and described the preferred embodiments of my invention, it is to be understood that I do not limit myself to the precise constructions herein disclosed and the right

is reserved to all changes and modifications coming within the scope of the invention as defined in the appended claims.

Having thus described my invention, what I claim as new, and desire to secure by United States Letters Patents is:

1. A book mark comprising a U-shaped member providing opposing material gripping jaws having terminals spaced longitudinally from each other and provided with curled ends adapted to engage a book part, said U-shaped member having a loop on the bend part thereof, hinge lugs secured to said member inwardly of said loop, a lever pivoted to said lugs and provided with a loop engaging the loop of the member to close said jaws against a part placed between the same, and a page locating book mark pivoted on the outer end of the lever, the U-shaped member being adapted to grip the flexible hinge of a book.

2. A book mark comprising a U-shaped member having opposing jaws adapted to be placed astride the flexible hinge of a book, means for forcing the jaws of said member against the hinge including a lever pivoted to said U-shaped member, and a page locating member pivoted to said lever.
